ESCUCHEON PLATE

Francis M. Mair, Berkeley, Calif., assignor to Schlage
Lock Company, a corporation

Application January 23, 1957, Serial No. 44,583

Term of patent 14 years

(Cl. D50—6)

Fig. 1 is a perspective view of an escutcheon plate showing my new design.

Fig. 2 is a front elevation of Fig. 1.

Fig. 3 is an end elevation of Fig. 1.

Fig. 4 is a cross section taken along lines 4—4 of Fig. 2.

I claim:

The ornamental design for an escutcheon plate, as shown.
